UNITED STATES PATENT OFFICE.

THOMAS STANLEY, OF STOKE-ON-TRENT, ENGLAND, ASSIGNOR OF ONE-HALF TO
THOMAS SLATER WHITFIELD, OF BASFORD, STOKE-ON-TRENT, ENGLAND.

BRICKMAKING AND LIKE PRESS.

Application filed March 7, 1924. Serial No. 697,654.

To all whom it may concern:

Be it known that I, THOMAS STANLEY, a subject of the King of Great Britain and Ireland, residing at 177 Sneyd Street, Cobridge, Stoke-on-Trent, England, have invented certain new and useful Improvements in and Relating to Brickmaking and like Presses, of which the following is a specification.

This invention relates to brick making and like presses and has for its object to provide improved means of effecting the necessary lubrication of the mold table and the blocks of molded material previous to their passage into the press.

According to the invention the pusher by which the blocks of molded material are transferred from the revolving mold table, is formed as or provided with an oil receptacle adapted for the feed of oil to wicks of absorbent material carried thereby in such manner that in the forward movement of the pusher for the transfer of the blocks of molded material, the wicks are traversed across the face of the plungers by which the said blocks are ejected from the mold table, so that thus the faces of the plungers are lubricated, while upon the return movement of the pusher the wicks or the like are carried across the face of the blocks of molded material which are contained in the succeeding molds or recesses of the revolving mold table.

According to the invention moreover the pusher is advantageously formed as the oil receptacle and is provided at the lower end with a holder or holders for the wicks or the like which are advantageously disposed in an inclined position.

It will be understood that the invention is applicable to all kinds of brick making and like machines in which a reciprocating pusher is provided, whether this is used to effect the transfer of the molded block from the mold table to the press, or to the delivery device after treatment by the press. While it is of advantage to form the pusher as the oil receptacle, it will be understood that a separate oil receptacle provided with a plurality of wick holders or adapted to feed to wick holders may be employed.

The application of the invention is illustrated, by way of example, in the accompanying drawings.

Figure 1 is a diagrammatic sectional eleva-

tion of a brick making press fitted with a pusher provided according to the invention.

Figure 2 is a plan view of a particular construction of pusher.

Figure 3 is an elevation corresponding to Figure 2.

Figure 4 is an end elevation.

Figure 5 is a plan view illustrating an existing pusher modified to accord with my invention.

Figure 6 is an elevation corresponding to Figure 5.

Figure 7 is a plan view of a modified construction of pusher constructed to accord with the invention.

Figures 8 and 9 are respectively views in front elevation and end elevation corresponding to Figure 7.

In carrying the invention into effect in the manner illustrated in the drawings, the mold table *a* of the press, which is adapted to rotate immediately before the movement of the plungers of the finishing press *b*, is provided with a series of molds *a*¹ for the reception of the raw material from the mixing apparatus and pug mill, such molds being fitted with rising plungers *c* forming the respective bottoms of the molds *a*¹ and adapted to be operated from the motion shaft *b*¹ of the finishing press by such means as an eccentric *c*¹ serving to oscillate an operating lever *c*² adapted to engage the downwardly protruding stems of the plunger bodies *c* as the molds *a*¹ are moved into the position for delivery of their contents to the finishing press. The pusher *d* is provided as a rectangular hollow body having two bearing sleeves *d*¹ by which it may be supported and guided upon horizontally disposed guide rods *e* situated above the surface of the mold table *a*. A reciprocating movement is given to the pusher through a suitable operating lever *f* or other mechanism from an eccentric *g* or like driving gear operated from the motion shaft *h* of the mold table or the press or from a separate motion shaft.

The bottom or lower plate *d*² of the pusher, which may be formed integral with the body *d* or fitted thereto in any suitable manner, is provided with a series of holes *d*³ serving as tubular wick holders for wicks *d*⁴ which extend into the body of the pusher and also below the lower face to a point in proximity

with the surface of the mold table *a*, so that they may drag on the surface of the mold table or plunger. The said wick holes or holders are advantageously inclined to

5 the surface of the mold table as indicated in the drawings. The wicks may be provided of any suitable material such as cloth, felt, fibre or the like.

The invention may advantageously be applied in the manner illustrated in Figures 5 and 6 to machines provided with pushers formed as hollow bodies, by closing the lower end of the pusher with a plate *i* formed with the wick holes *i*¹ or provided with tubes 10 or holders, the said plate being bolted in position with intermediate packing *i*² of rubber or other suitable material by means of bolts *i*³ which extend through the body of the pusher to engage with transverse bars 15 or plates *i*⁴ disposed on the upper surface of the pusher.

In the construction of pusher illustrated in Figures 7, 8 and 9, the body is formed as an open rectangular fitting *j* upon the forward face of which in the middle is a dovetail recess or groove *j*¹ adapted to receive wood packing for contacting with the blocks of molded material from the mold table. Two guide sleeves *k* are also provided at the 30 front of the pusher and formed with strengthening webs *k*¹. The sleeves *k* are connected by a bridge piece *l* upon which are mounted the lugs *m* by which connection with the operating lever may be made. The bottom of the fitting *j* is closed by 35 means of a wick plate *n* secured to the fitting *j* by means of screws *n*¹, a layer of packing being interposed. The wick plate *n* is formed with two longitudinal ribs *n*² 40 on the lower face in which are formed wick holes or tubes *n*³ which advantageously are inclined forwards and rearwardly as indicated in Figure 9. The end walls of the fitting *j* may be inclined outwardly so that 45 the lower face may be thus elongated to cover a wider surface in the movement of reciprocation of the pusher.

It may be advantageous in certain cases to provide wick tubes or holders separately 50 formed to receive the wicks instead of disposing the wicks or the like within holes or slots formed within the bottom of the pusher or in the plate forming the said bottom. Such wick holders may be mounted 55 adjustably in the bottom plate of the pusher.

It will be understood that the invention

is applicable also to presses in which the press plunger or ram operates upon the molded block while it is still within the mold.

60

Any suitable oil may be used such as that usually sold as brick press oil.

I claim:

1. In a brick making press having a rotary mold table, a pusher horizontally reciprocated above the said table for transferring the blocks of molded material from the said table, said pusher comprising an oil receptacle, a plurality of openings through the bottom of the said receptacle, wicks inserted into said openings and means for supporting the pusher above the table so that the wicks are maintained in contact therewith.

65

2. In a brick making press having a rotary mold table, a pusher horizontally reciprocated above the said table for transferring the blocks of molded material from the said table, said pusher comprising an oil receptacle, a plurality of openings inclined to the surface of the mold table in the direction of travel of the said pusher in the bottom of the said receptacle, wicks inserted into said openings and means for supporting the pusher above the table so that the wicks are maintained in contact therewith.

75

3. In a brick making press having a rotary mold table, a pusher horizontally reciprocated above the said table for transferring the blocks of molded material from the said table, said pusher comprising an oil receptacle, a plurality of series of openings in the bottom of the said receptacle, wicks inserted into said openings and means for supporting the pusher above the table so that the wicks are maintained in contact therewith.

80

4. In a brick making press having a rotary mold table, a pusher horizontally reciprocated above the said table for transferring the blocks of molded material from the said table, said pusher comprising an oil receptacle, a plurality of series of openings in the bottom of the said receptacle, said series of openings being oppositely inclined in the direction of travel of the said pusher, wicks inserted into said openings and means for supporting the pusher above the table so that the wicks are maintained in contact therewith.
